FRANZ STOLP, OF BERLIN-PANKOW, GERMANY, ASSIGNOR TO SIEMENS AND HALSKE AKTIENGESELLSCHAFT, OF SIEMENSSTADT NEAR BERLIN, GERMANY, A COMPANY OF GERMANY

SPOOL FOR ELECTRICAL COILS

Application filed May 8, 1931, Serial No. 535,830, and in Germany June 7, 1930.

The invention relates to spools for electrical coils which are substantially so assembled from individual parts without gumming or pressing that the spools are stable 5 in themselves whereby a coil support part can be formed as a terminal block.

Methods hitherto known consisted of a member carrying the winding for instance of prismatic form, notched at the top and bottom and bent over and provided with a flange 10 by gumming or pressing. The manufacture of spools of this kind necessitated various operations and special machines and was frequently very difficult just according to the 15 nature of the manufacturing material. The manufacturing costs of such spools were consequently comparatively high. Particular difficulties were met with in the manufacture of spools capable of withstanding the tropics 20 and high tension which in order to comply with atmospheric or voltage conditions had to be manufactured from bakelite-hard paper which did allow the separate parts sticking together or if so only under exceptional conditions. Spools of this type mostly 25 consisted of moulded insulation or a metallic member provided with bakelite-hard paper flanges and covered with insulating paper or rubber.

In accordance with the invention these 30 defects are removed and the manufacturing costs reduced in this way that the spools are assembled from a plurality of flat blanks which yield stable members without gumming 35 or pressing operations. Since the spools are assembled immediately prior to winding which is done in a few moments and is therefore not to be considered as a special operation the manufacturing costs are limited solely 40 to material and stamping costs. Bakelite-hard paper can also be employed as manufacturing material for the method according to the invention and spools capable of resisting the tropics and high tension can thus 45 be manufactured without difficulty. In re-

spect to methods hitherto employed these spools not only stand out owing to their low manufacturing costs but also owing to considerably increased reliability of operation. A further simplification in respect to methods 50 hitherto known is accomplished in this way that a part of the coil support can be formed as a terminal block whereby a special connecting strip and the fixing means necessary for same are dispensed with. 55

In the drawing which shows spools of prismatic form,

Fig. 1 is an end elevational view of a completed spool;

Fig. 2 is a side view of the spool shown in 60 Fig. 1;

Fig. 3 is a top plan view of one embodiment of the invention showing a spool equipped with shelves having terminals supported thereon; 65

Fig. 4 is an end elevational view of another embodiment of the invention in which a wound prismatic member is supported between upper and lower stamped out flat parts; and 70

Figs. 5, 6 and 7 are flat surface views of the stamped out parts necessary to form the spools shown in Figs. 1 and 2, Figs. 5 and 6 being the flat sides, two of each of which are required to form the prismatic barrel of the 75 spool and Fig. 7 being one of the spoolheads. The small apertures shown across the top of the spoolhead in Fig. 7 are provided for the accommodation of ends of coil windings to be supported on the spool. 80

In one embodiment of this invention, namely that which is illustrated by Figs. 1 and 2, two flat blanks *a* and *a'* of the form shown in Fig. 5 each provided with hollows *b* and *b'* formed in edge portions of the blank and extensions *c* and *c'* extending from ends of the blank are placed diagonally through an aperture *d* of two flanges *e*, *e'* of the form shown in Fig. 7 and so arranged 85 that the blank *a* lies against the edge *A* and 90

the blank a' against edge B of both flanges. The extensions c and c' of each of the parts a and a' project beyond and normal to the outer faces of the flanges e and e' , respectively, the part a resting on the edges A of the flanges e and e' and the part a' resting on the edges B of the flanges e and e' . The side parts of the coil carrier still lacking and necessary to form the prismatic barrel of the 10 spool are formed by two rectangular parts f and f' each provided with a tooth g on their sides as shown in Fig. 6.

These side parts f and f' are so arranged that shifting into the flanges e and e' is again 15 carried out diagonally and the teeth g are then pressed into the hollows b or b' of part a and b and b' of part a' . The result is a box-like structure provided with flanges such as shown in Figs. 1 and 2. Shifting of the 20 flanges inwardly is prevented by a strip of sufficiently strong insulating paper which serves at the same time as a winding support.

If the spool is to be provided with terminals the part a which rests on the edges 25 A of both flanges is replaced by a part h whose extensions corresponding to the extensions c, c' of Fig. 5 are considerably increased to form comparatively wide shelves. These shelves are provided with terminals or clamping pieces for terminations of ends of windings to be supported on the spool and for attachment of wires of an outside circuit. Fig. 30 3 shows a spool constructed in this way.

Fig. 4 shows an end elevational view of a 35 spool in which the side parts f, f' of the form shown in Fig. 6 have been replaced by a wound prismatic member i . The wound prismatic member i is inserted between the parts a and a' and forms with these parts a and a' 40 the barrel of the spool. In this constructional form it is not necessary to provide parts a and a' with hollows b, b' .

What is claimed is:

1. A spool for electrical coils comprising 45 four separate flat plates and two flanges and in which the four plates are held together by the flanges.

2. A spool for electrical coils comprising 50 a set of four separate flat plates forming a prismatic barrel of the spool, and end flanges and in which the plates are provided with teeth engaging each other.

3. A spool for electrical coils comprising 55 a set of plates and end flanges, said plates having portions extending in the same plane as the plates and normal to the flat outer faces of the end flanges and bearing against the outer side of the flanges to hold said 60 flanges and plates in assembled form.

4. A spool for electrical coils comprising 65 individual flat plates forming a prismatic coil carrier and end flanges therefor, one of the plates of said coil carrier having a portion extending in the same plane as the plate

and beyond an end flange to form a terminal block.

5. A spool comprising spoolheads, a pair of spaced flat plate members extending between said spoolheads, and a prismatic member inserted between said spaced flat plate members, said prismatic member maintaining said plate members in spaced relationship and forming therewith a prismatic barrel for the spool.

In witness whereof, I hereunto subscribe my name this 9th day of April, 1931.

FRANZ STOLP.
